STOCKING-KNITTING MACHINE. **BEST AVAILABLE COPY**

1,149,714.

Specification of Letters Patent.

Patented Aug. 10, 1915.

Application filed June 4, 1914. Serial No. 843,060.

To all whom it may concern:

Be it known that I, GEORGE P. BOSWORTH, citizen of the United States, residing at Central Falls, Rhode Island, have invented 5 certain new and useful Improvements in Stocking-Knitting Machines, of which the following is a specification.

The invention is designed to make a fullness or gore at the back of the stocking at a 10 point preceding the heel pocket the line of which will run at an inclination to the leg, and the invention consists in the features and combination and arrangement of parts hereinafter described and particularly 15 pointed in the claims.

The invention is shown in connection with a machine of the Banner type made under Letters Patent of the United States, granted to Hemphill #933,443, dated September 7, 20 1909, though it will be understood that the invention is applicable to machines of other makes.

In the accompanying drawings, Figure 1 is a diagrammatic view of a stocking showing the gore as produced in my machine. Fig. 2 is a front view of a knitting head and certain operating connections embodying my invention. Fig. 3 is an end view of 30 part of the knitting head of Fig. 2, with some of the operating connections and pattern cams. Fig. 4 is a plan view of the knitting head partly in section and parts being omitted. Fig. 5 is a diagrammatic development of the knitting cams.

As shown in Fig. 5, the needle cams comprise the ordinary stitch cams 1, 2, the guard cam 3, and the needle lowering cam 4. This lowering cam is combined with an instep cam 5 which is to elevate the instep needles 40 which are to be rendered inoperative, this cam, as in usual practice being raised and lowered with the lowering cam 4, but said cam is modified in its construction and operation as hereinafter will be noted. The cams 4 and 5 are both carried by a block 4^a 45 slidable in a post 4^b, said block being shifted by a bell crank lever 4^c through the connections usual in the Banner machine. The needle cam set also includes a fixed cam 6 for completing the elevating of the instep needles to their inoperative plane when raised by the instep cam 5, and also the supplemental needle raising cam 8 which is 50 movable vertically on the outside of the usual cam ring 9. The narrowing picks 10

and widening picks 11 are of usual construction. The needle circle rotates in the arrow direction shown in Figs. 4 and 5.

The needles are in three sets in respect to the length of their butts. As shown in 60 Fig. 4, there are short butt needles *a*, medium length butt needles *b*, *b*, and long butt needles *c*. The long butt needles occupy one-half of the needle circle, and the other half of the needle circle is made up of the 65 short butt needles *a*, and the medium length butt needles *b*, *b*. Furthermore, there are two columns of the medium butt needles *b*, *b*, and one of these columns is located at one end of the column of shortest butt 70 needles *a*, and the other column of medium butt needles is located at the other end of the said column of short butt needles *a*.

In round knitting all the needles pass along with their butts in the normal path 12, 75 Figs. 2 and 5, at the top of the cam ring 9, said butts passing below the lowering cam 4, and below the cam 6 being elevated by the cam 2 to take the yarn, after which they pass under the guard cam 3 and are retracted to form stitches by the cam 1. On reciprocating knitting, as in usual practice, when the needles rotate in the direction opposite to the arrow, they are elevated to take the thread by cam 1, and are retracted 80 to form the stitches by the cam 2.

In order to make the fullness or gore indicated by the line *x*—*x'* Fig. 1, all the needles are elevated to inoperative position excepting the shortest butt needles *a*. For 90 thus elevating the long butt and medium butt length needles the cam 8 is raised at the time the shortest butt needles are passing it. As the shortest butt needles *a*, are passing the supplemental cam 8, this cam 95 is raised, without elevating these needles because they are too short to reach this cam. When one of the columns of the medium butt needles *b*, come around immediately following the shortest butt needles they will be 100 elevated to inoperative position by the said supplemental cam, these needles projecting slightly beyond the spacing cam ring 9, on which the butts ordinarily slide. Following the column of medium butts which are 105 raised, as just described, are the long butts and following these is the other column of medium butts so that all the medium butt needles of both columns will be raised to inoperative position, and the same is true of 110

the half circle of long butt instep needles. The long butt needles *a*, as usual, are the instep needles and the medium and short butt needles constitute the heel and toe or sole needles, and of course they are the needles which make the extra gore also. During the raising of the medium and long butt needles the widening picks are in their elevated position, their controller 13 being elevated by connections from the cam, (their springs tending constantly to swing the said picks up, as presently described,) on the pattern drum shaft. The ordinary instep cam 5 is now raised. This cam sets in far enough to take only the long butt needles *c*. It misses both the short butt needles *a*, and medium butt needles *b*. This instep cam while raised on this revolution, is not effective because the long butt needles have been already raised by the supplemental raising cam 8. It is raised because in ordinary practice the machine is about to go on reciprocating knitting and it must remain elevated during this time, otherwise the lowering cam, with which it is combined, being secured to the same post, or block, would lower the needles. This lowering cam is located close to the cylinder and will lower all needles when it occupies its lowermost position shown in Fig. 5. We now have all the needles raised to inoperative position excepting the shortest butt needles, which make the back of the tube. The supplemental raising cam 8 now falls. The machine now goes on reciprocating knitting and as the widening picks are in their elevated or operative position widening will be done on these picks, two medium butt needles *b* being lowered from their elevated position by each widening pick from the ends of the columns of medium butt needles on each stroke of the machine and the narrowing picks raising one of these two needles back again to elevated or operative position, the net result of which is that on each stroke the fabric will be widened one needle. This widening goes on upon all medium butt needles, first on one column thereof and then the other until all these medium butt needles have been brought into work and the fabric has been widened from *x* to *x'*. At the end of these widening actions the widening picks are thrown down out of action by moving their controller 13 down, the arms of which overlie the stems of the picks, and therefore as the machine continues to reciprocate the widening picks will be out of operation but the narrowing picks will continue to work and therefore the narrowing actions will be proceeded with in the ordinary way from *x'* to *y*, followed by the widening back from *y* to *x'*, to make the heel pouch, as in ordinary practice. During this narrowing and widening action the instep lowering cam 4 will re-

main up to thus prevent lowering the long butt elevated needles. Picking is done only on the medium butt needles. After the widening has been completed the instep cams 4 and 5 are lowered to lower all the instep needles, the other medium butt needles having been lowered one by one on the widening action and the shortest butt needles having remained down in action during all the above actions of forming the high splice heel pocket, and the widening picks being now moved down to inoperative position the machine goes on round knitting to make the foot.

When the toe pocket is to be formed the instep cam 5 is raised to elevate the long butt needles, this cam, as above stated, missing the medium and short butt needles and then narrowing and widening goes on in the usual way, but upon the medium butt needles, these medium butts, as before described, being separated into two columns and lying on each side of the shortest butt needles which remain in work. In forming the toe the usual instep cam, as just stated, raises the long butt needles as in ordinary practice. The supplemental raising cam is not operated at this time because the medium butts are the ones to be picked upwardly for narrowing, and they must be left down so as to be acted on and elevated one by one by the narrowing picks as in ordinary practice.

It will be seen from the above that for making the diagonal gore *x*—*x'* I elevate at once, by the supplemental cam 8, the long butt instep needles and also all the medium butt needles which are to be used for widening the fabric, leaving only the smallest number of needles in operation, *i. e.* the shortest butts, and by throwing into operation the widening picks a widening action begins at once, no narrowing preceding the widening as is ordinarily the case in forming a heel pouch or toe pocket.

The three lengths of needle butts are essential in order to provide a space for the supplemental cam 8 to rise through. This is provided by the short butt needles, the cam being raised as these needles are passing it and thus the cam is up in position to raise the medium butt needles and the long butt needles before these come to the cam, and these needles are definitely raised at one point. Furthermore, by using the three length butts of needles the short butts remain in action while there is provided on each end of this column of active needles a column of medium butt needles on which picking is done, and between these two columns of medium butt needles the long butt instep needles are disposed.

Pattern cams.—Referring to Fig. 3, I show the pattern cams for controlling the supplemental needle raising cam 8, and the

widening picks 11, the former cam being indicated at 14, and the latter being indicated at 15, in dotted lines, this latter cam being substantially the same as in the Hemp-
5 hill patent for making the ordinary heel pocket, excepting that a block is inserted at 16, to maintain the widening pick controller 13 up for a longer time than ordinarily, in order to widen for the extra gore. The cams 10 rotate in the arrow direction step by step, and following the block 16 the lever 17 drops into the notch 18 for the heel narrowing, the widening picks 11 being thus lowered out of operation by the controller 15 13, forcing them down against the tension of their usual springs 19. This controller, as is ordinarily the case, bears on the stems of the widening picks. Following the notch 18 the lever 17 is raised at 20, thus allowing 20 the widening picks to raise to operative position under tension of their springs 19 when the controller 13 is lifted. The lever 17 next drops into the recess 21 to inoperative position for round knitting for the foot. 25 The next movement of the pattern cam 15 brings the space 22 beneath the lever 17 for the toe narrowing. The next step brings the high point 23 beneath the lever, raising it for the toe widening and following this 30 the machine goes on round knitting, the widening picks lowering at 24 and immediately raising at 25 for round knitting of the leg. The needle cam 8 is moved vertically in a guide box 26 by a lever 27, pivoted at 35 28, and operated through link 29, lever 30, link 31 and lever 32, suitably pivoted to the frame, said lever being operated by the cam block 14 on the pattern drum. The lever 17, above mentioned, which controls 40 the position of the widening picks, operates through a link 33, lever 34 and pin 35, which is slideable vertically in a suitable bracket, this controller being mounted on a block 36.

I claim:

45 1. In a circular stocking knitting machine, a needle cylinder, needles comprising a column of short butt needles, a column of medium length butt needles at each end of the column of short butt needles, said needles forming one half of the needle circle, a column of long butt needles forming the other half of the needle circle, narrowing and widening picks, means for elevating the long butt needles and the medium butt needles for the formation of a gore previous to the formation of the heel, means for controlling the widening picks to widen on the medium butt needles for making said gore and means for then controlling the picks to narrow and widen the fabric for the formation of the heel, substantially as described.

2. In a circular stocking knitting machine, a needle cylinder, needles comprising a column of short butt needles, a column of medium length butt needles at each end of

the column of short butt needles, said needles forming one half of the needle circle, a column of long butt needles forming the other half of the needle circle, narrowing and widening picks, means for elevating the long butt needles and the medium butt needles for the formation of a gore preceding the heel pocket, and means for controlling the widening picks to widen on the medium butt needles for making said gore, and means for raising the long butt needles only, prior to knitting the toe, substantially as described.

3. In a circular knitting machine, a needle cylinder, needles with three lengths of butts, comprising a column of short butt needles, a column of medium butt needles at each end of the column of short butt needles, a column of long butt instep needles, instep raising and lowering cams, said raising cam acting on the long butt needles and said lowering cam acting upon all the needles, a supplemental raising cam acting to raise to inoperative position the medium butt needles, and narrowing and widening picks acting upon the medium butt needles, means for operating the supplemental cams to elevate the medium butt needles and means for controlling the widening picks for the formation of a gore preceding the heel pocket, said cam being lowered during the formation of the heel and toe by narrowing and widening, substantially as described.

4. In combination in a stocking knitting machine, needles having three lengths of butts, long butts, medium butts and short butts, a lowering cam and two cams for raising the needles to inoperative positions, and independent connections for operating said needle raising cams, and narrowing and widening picks, one of said cams raising the long and medium butt needles to inoperative position at the heel, and the other raising only the long butt needles for the formation of the toe pocket, substantially as described.

5. In combination in a stocking machine, needles comprising a half circle of long butt needles, a half circle made up of a column of short butt needles with a column of medium butt needles at each end of the column of short butt needles, a raising cam to raise the long butt needles only, a lowering cam to lower any elevated needles, a sliding block carrying said cams, a post in which said block slides, means for raising and lowering the block, a cam for elevating the long and the medium butt needles, means for operating said cam to lift said needles for the making of a gore preceding the formation of the heel, said cam being immediately lowered after raising the said needles, pick mechanism for widening on the elevated medium butt needles, said pick mechanism then narrowing and widening the fabric for the heel.

pouch, following which the lowering cam falls for round knitting, the said operating means raising only the raising cam and lowering cam at the toe for elevating only 5 the long butt needles while the toe pouch is formed on the medium and short butt needles and while the elevating cam last mentioned remains down, and pattern mech-

anism for giving the cams the adjustment mentioned, substantially as described.

In testimony whereof I affix my signature in presence of two witnesses.

GEORGE P. BOSWORTH.
